UNITED STATES PATENT OFFICE.

HORACE SHEBLE, OF PHILADELPHIA, PENNSYLVANIA.

SOUND-BOX FOR TALKING-MACHINES.

1,158,316.

Specification of Letters Patent. Patented Oct. 26, 1915.

Application filed March 5, 1915. Serial No. 12,245.

To all whom it may concern:

Be it known that I, HORACE SHEBLE, a citizen of the United States, residing in Philadelphia, Pennsylvania, have invented certain Improvements in Sound-Boxes for Talking-Machines, of which the following is a specification.

The object of my invention is to so construct a talking machine sound box as to tend to maintain in one position the lever which carries the stylus or needle and to return said lever to such position when it has been deflected therefrom. This object I attain in the manner hereinafter set forth, reference being had to the accompanying drawing, in which—

Figure 1 is a face view, on enlarged scale, of a sound box constructed in accordance with my invention; Fig. 2 is an edge view 20 of the same, looking in the direction of the arrow Fig. 1; Fig. 3 is a transverse section of the sound box and part of the tone arm connected thereto, and Fig. 4 is a sectional view on the line *c*—*c*, Fig. 2.

The construction of the sound box is shown in Fig. 3, on reference to which it will be observed that the hollow body of the box contains the usual diaphragm 2^a the peripheral portion of which is confined between rings 40 and 41 of rubber or other elastic material, the supporting ring 40 which contacts with the inner face of the diaphragm being contained in a groove in the base of the sound box and the confining ring 41 which bears upon the outer face of the diaphragm being held in contact therewith by the annular cap or cover plate 2^b. The base of the sound box has a curved passage 2^c which communicates with the tone arm 3 and the bearing head at the inner end of the needle carrying lever 42 rests upon or is secured to the center of the diaphragm above the entrance to said passage 2^c, as shown in Figs. 1 and 3.

The needle carrying lever 42 has an enlarged head 43 in which is formed the socket for the reception of the needle, the latter being secured in place by means of a confining screw 44, and the needle carrying lever is retained in its normal position by reason of its engagement with the elastic fulcrum members, the opposite sides of the head 43 of the needle carrying lever having formed therein V-shaped recesses for the reception 55 of the V-shaped ends of the inturned upper portions 45 of the side members 46 of an

elastic yoke whose base member 47 is secured to an arm 48 projecting from the sound box 2, this method of mounting the needle carrying lever being best shown in Figs. 1, 2 and 4 of the drawing.

Connecting the opposite arms 46 of the elastic yoke is a bolt 50 having at one end a head 51 and at the other end a nut 52, the latter being adapted to the threaded end 65 of the bolt so that by adjustment of the nut the pressure of the V-shaped ends of the members 45 of the yoke can be varied, the elasticity of those portions of the yoke intervening between its bearing points and the bolt 50, however, constituting a factor in the vibratory movements of the needle lever.

That portion of the needle lever 42 intervening between the fulcrum of the lever and its point of contact with the sound 75 box diaphragm 2^a is so much greater than the distance between the fulcrum of the lever and the point of the needle carried thereby as to properly amplify the vibrations imparted to the needle.

The V-shaped ends of the spring contact fulcrum of the needle carrying lever bite into the latter and cause its vibrations to be imparted to the spring, whose torsional resistance thus tends to constantly maintain 85 the lever in one position and to return it to such position when it has been deflected therefrom, the result being a prompt response of the needle to the conformation of the record groove and a correspondingly 90 perfect reproduction of the sounds from which the record was produced.

I claim:

1. A talking machine sound box having a needle carrying lever with a frictional 95 spring contact fulcrum which exercises torsional control of the lever.

2. A talking machine sound box having a needle carrying lever, with a frictional spring contact fulcrum comprising elastic 100 fulcrum members having pointed ends which are caused to engage the sides of the needle carrying lever.

3. A talking machine sound box having a needle carrying lever with a pointed frictional spring contact fulcrum which ex- 105 ercises torsional control of the lever.

4. A talking machine sound box having a needle carrying lever, with a spring contact fulcrum comprising elastic fulcrum 110 members having pointed ends which are caused to engage the sides of the needle car-

rying lever, and means for varying the pressure of said pointed ends against the lever.

5. A talking machine sound box having a needle carrying lever, and an elastic yoke having inturned arms which engage said lever and serve as a fulcrum therefor which exercises torsional control of the lever.

6. A talking machine sound box having a casing, a diaphragm, means for retaining 10 said diaphragm at its peripheral portion, a needle carrying lever, and a frictional spring contact fulcrum for the latter which exercises torsional control of the lever.

7. A talking machine sound box having 15 a needle carrying lever, and an elastic fulcrum for the latter, comprising opposite elastic members having pointed ends which are caused to engage the sides of the needle carrying lever and serve to transmit the

vibratory movements of the latter to said fulcrum.

8. A talking machine sound box having a needle carrying lever, and an elastic fulcrum mounting for the latter comprising elastic fulcrum members having pointed 25 ends which are caused to engage the sides of the needle carrying lever and tend to maintain said lever in one position, and also to return it to such position when deflected therefrom.

In testimony whereof, I have signed my name to this specification, in the presence of two subscribing witnesses.

HORACE SHEBLE.
